(57) **CLAIM**

The ornamental design for a bowl with a utensil retention feature, as shown and described.

DESCRIPTION

This Design Application is also related to co-pending U.S. Design patent application Ser. No. 29/428,184, filed on Jul. 27, 2012, entitled Bowl With Utensil Retention Feature; U.S. Design patent application Ser. No. 29/428,185, filed on Jul. 27, 2012, entitled Bowl With Utensil Retention Feature; U.S. Design patent application Ser. No. 29/428,187, filed on Jul. 27, 2012, entitled Bowl With Utensil Retention Feature; U.S. Design patent application Ser. No. 29/428,188, filed on Jul. 27, 2012, entitled Bowl With Utensil Retention Feature; U.S. Design patent application Ser. No. 29/428,189, filed on Jul. 27, 2012, entitled Bowl With Utensil Retention Feature; U.S. Design patent application Ser. No. 29/428,221, filed on Jul. 27, 2012, entitled Bowl With Utensil Retention Feature; U.S. Design patent application Ser. No. 29/428,222, filed on Jul. 27, 2012, entitled Bowl With Utensil Retention Feature; U.S. Design patent application Ser. No. 29/428,225 filed on Jul. 27, 2012, entitled Bowl With Utensil Retention Feature; U.S. Design patent application Ser. No. 29/428,227, filed on Jul. 27, 2012, entitled Bowl With Utensil Retention Feature; U.S.

Design patent application Ser. No. 29/428,232, filed on Jul. 27, 2012, entitled Bowl With Utensil Retention Feature; U.S. Design patent application Ser. No. 29/428,240, filed on Jul. 27, 2012, entitled Bowl With Utensil Retention Feature; U.S. Design patent application Ser. No. 29/428,244, filed on Jul. 27, 2012, entitled Bowl With Utensil Retention Feature; U.S. Design patent application Ser. No. 29/428,248, filed on Jul. 27, 2012, entitled Bowl With Utensil Retention Feature; U.S. Design patent application Ser. No. 29/428,253, filed on Jul. 27, 2012, entitled Bowl With Utensil Retention Feature; U.S. Design patent application Ser. No. 29/428,256, filed on Jul. 27, 2012, entitled Bowl With Utensil Retention Feature; U.S. Design patent application Ser. No. 29/428,261, filed on Jul. 27, 2012, entitled Bowl With Utensil Retention Feature; U.S. Design patent application Ser. No. 29/428,270, filed on Jul. 27, 2012, entitled Bowl With Utensil Retention Feature; U.S. Design patent application Ser. No. 29/428,276, filed on Jul. 27, 2012, entitled Bowl With Utensil Retention Feature; and

U.S. Design patent application Ser. No. 29/428,279, filed on Jul. 27, 2012, entitled Bowl With Utensil Retention Feature. The disclosure of these Design Applications are considered part of and are incorporated by reference in the disclosure of this design application.

FIG. 1 is a top perspective view of a bowl with a utensil retention feature;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof; and,

FIG. 8 is an enlarged, broken away view of area 8 on FIG. 1. The broken lines are included for illustrative purposes only and form no part of the claimed design.
